FLASHLIGHT

Herman G. Graubner, New York, N. Y., and Albert G. Saurwein, Cleveland, Ohio, assignors, by mesne assignments, to Union Carbide and Carbon Corporation, a corporation of New York

Application July 5, 1935, Serial No. 29,792

11 Claims. (Cl. 240—10.69)

The invention pertains to flashlights and more specifically to the mechanism thereof for controlling the luminous condition of the lamp bulb and the character of the beam of projected light.

5 When a flashlight is provided with a reflector that concentrates the projected light beam into a small area it is unsatisfactory for near-by use on account of the small area illuminated, and when the light beam covers a large area it is 10 unsatisfactory for distant use on account of the low intensity of the light beam. In order to provide both kinds of illumination in one flashlight a diffusing screen that may be moved at will into the path of the light rays passing from the lamp 15 bulb to a concentrating reflector has been proposed. In this construction a sliding member located on the outside of the flashlight has been employed to move the screen and thus control the character of the projected light beam, and a separate sliding member has been employed for closing 20 and opening the electric circuit through the lamp bulb to control its luminous condition. But two operating buttons on the outside of the casing detract from the appearance of the flashlight, 25 cause confusion in selecting the one desired, and cause delay when it is desirable to operate both at the same time or in quick succession.

Therefore, the more important objects of the 30 invention are to provide an improved operating means for the screen and the switch that is less confusing, less complicated, and easier to operate. These and other objects and novel features will be more fully disclosed in the following specification and the accompanying drawing in which:

35 Fig. 1 is a side view of a flashlight embodying the invention with the central portion broken away to show the structure in section;

Fig. 2 is a fragmentary longitudinal sectional view through the means for securing the switch to 40 the casing showing how relative movement is effected; and

Fig. 3 is a sectional view along line 3—3 of Fig. 1.

As shown in the drawing the invention may be 45 embodied in a flashlight having a casing A, a reflector B, a lamp bulb C, and a switch D.

The casing A may be tubular in form and the reflector B may be mounted in the light projecting end in any suitable manner. The apex of the reflector B may be provided with a suitable opening 50 10 through which the globe of the lamp bulb C extends into operative relation with the reflector. The lamp bulb C may be mounted in a suitable socket 12 of conventional construction that is 55 rigidly secured to a supporting bridge 14. This

bridge may extend transversely across the casing A and be rigidly secured to the casing or to a diaphragm 16 that is in turn secured to the casing. The bridge 14 may be secured to the diaphragm 16 by any suitable conventional fastening such as rivets 17, and the diaphragm may be provided with a tubular extension 18 that is rigidly secured within the casing A, and also with a suitable axial opening 20 adjacent the opening 10 in the reflector through which the lamp bulb extends. 10 The bridge 14 may be electrically isolated from the socket 12 by any suitable means such as a plurality of dielectric washers 22

15 The character of the projected light beam may be controlled or changed by a diffusing screen 24 so mounted that it may be interposed at will between the lamp bulb C and the reflector B. This screen may be of any suitable translucent material such as frosted or whitish glass, frosted or whitish Celluloid, or a whitish resinous material 20 of which vinyl resin is preferred. The screen may be of any suitable shape that may be interposed between the lamp and reflector but a tubular or cylindrical shape is preferred, and, although the size may vary, one that will freely 25 pass through the annular space between the lamp bulb and the walls of the aligned openings in the reflector and diaphragm is preferred.

28 The screen may be supported by any suitable structure such as a support, bracket, or yoke 26 30 that encircles the lamp socket a suitable distance to the rear of the diaphragm and reflector, and the screen may be provided with a suitable rim 28 that extends outwardly from the rear thereof between the bracket 26 and a suitable clamp 30 35 that may be secured to the bracket by any conventional fastening such as a rivet 32. Although the rim 28 may be disposed at either side of the bracket 26, the relative location of the parts is facilitated when it is disposed at the rear 40 and the opening in the bracket closely surrounds the body of the screen.

45 The bracket 26 and the diffusing screen 24 may be moved with respect to the lamp bulb C and the reflector B in any suitable way such as by mechanically connecting the bracket or yoke 26 with a switch such as D that is movable as a unit with respect to the casing A to which the reflector and lamp bulb are fixed. Such a connection may be effected by providing the bracket 26 with an 50 actuating plate or strip 34 that extends along the inside of the casing to a position adjacent the switch to which it may be secured by a suitable number of rivets 36 that extend through aligned openings in the strip 34 and the housing 55

38 of the switch, and also through suitable slots or elongated openings 40 in the casing A. The casing may also be provided with a suitable opening in the portion covered by the switch through which electrical connection with the lamp bulb may be established, and the movement of the switch as a unit with respect to the casing may be limited by the length of the slots 40 or the strip 34 may be provided with a portion or stop 42 that engages the end of the opening in the casing underneath the switch.

In this flashlight the casing may form part of the conductor for the electric circuit including the lamp bulb, battery, and switch. In such flashlights a separate conductor is usually employed between the switch and the lamp bulb or lamp socket. This connection may be effected by a conductor 44 that extends from the switch to the lamp socket. The conductor 44 may be secured 20 to the strip 34 by a suitable number of partially encircling ears 46, and it may be electrically isolated from this strip by a suitable covering of dielectric material 48 and also by a suitable strip or sheet of dielectric material 50 interposed between the conductor and the strip. The portion of conductor 44 adjacent the switch may extend through a suitable opening 52 in strip 34 where it may be exposed to contact with a resilient switch arm 54 electrically connected with the casing and movable into contact with the conductor by depressing or manipulating a suitable operating button 56. The portion of conductor 44 adjacent the switch may be provided with an exposed contact surface 58 in operative relation with 30 switch arm 54, and the portion adjacent the lamp socket 12 may be provided with an exposed contact surface or portion 60 in electrical engagement with a suitable resilient conductor 62 rigidly secured to lamp socket 12.

40 In order to maintain the movable switch D and the diffusing screen 24 in any of their adjusted positions with respect to the casing A, the strip 34 may be provided with a resilient detaining member 64 in frictional engagement with 46 the inner surface of casing A. This detaining member may be of any suitable size or shape and it may be secured to the strip 34 by any suitable or conventional fastening such as a rivet 66.

In this flashlight, in common with others well known in the art, one pole of a suitable battery 68 is maintained in electrical connection with a portion of the flashlight in conductive relation with the casing A, and the other pole of the battery such as the central pole is maintained in electrical connection with the central terminal of the lamp bulb by a suitably insulated portion of the lamp socket, the other or outer terminal of the lamp bulb being connected with the outer portion or shell of the lamp socket. In the present flashlight, the outer shell 70 of the lamp socket 12 is connected with the resilient conductor 62, and when the switch D is in closed position the portion of the circuit from the outer terminal of the lamp bulb to the casing is through shell 70, resilient conductor 62, movable conductor 44, and switch arm 54.

The luminous condition of the lamp bulb may be controlled by depressing the switch control button 56 thereby closing the circuit through the 70 lamp filament and the energizing battery. Thus by a suitable manipulation of this button the luminous condition of the lamp bulb may be controlled at will. Also, by exerting a forward pressure on this button or on the switch housing, sufficient to move the switch along the casing, the

diffusing screen may be moved into the path of the light rays falling upon the reflector. Thus the luminous condition of the lamp bulb and the character of the projected beam of light may be controlled either independently or simultaneously. When the diffusing screen is in forward or operating position the light rays are sufficiently dispersed to produce a relatively wide beam of substantially uniform intensity, and when the screen is in its rear or inoperative position the reflector concentrates the light into a relatively narrow beam of much greater intensity. Since the character of the light beam may be controlled while the circuit is closed all delay in changing from one operating button to another is 15 obviated. Also, since but one button is provided, all confusion regarding the selection of the desired button is obviated. Therefore, it appears that the objects of the invention are obtained in an efficient and reliable manner.

20 It is understood, however, that the form and relative location of the parts may be changed, and that similar and equivalent materials and elements may be employed in the place of those described.

25 We claim:

1. In a flashlight; a casing; a lamp bulb mounted in said casing; a diffusing screen movably mounted in said casing in operative relation with said lamp bulb; a member movably mounted on said casing; and means rigidly connecting said screen and said member for movement as a unit relatively to said lamp bulb to control the character of the projected light beam, said member including means continuously controlling the circuit to said lamp bulb in all positions of said member.

2. In a flashlight; a casing; a reflector mounted in said casing; a lamp bulb mounted in said casing in operative relation with said reflector; a diffusing screen mounted in said casing in operative relation with said lamp bulb; and a switch mounted upon said casing; said switch being bodily movable with respect to said lamp bulb and being relatively fixed with respect to said screen whereby the screen may be shifted by bodily movement of the switch for controlling the character of the projected light beam; said switch including means for controlling the circuit to said lamp bulb in all positions of said switch in its bodily movement.

3. The flashlight claimed in claim 1 in which the last-named means includes an operating button and a pair of switch contacts movable as a unit with said member.

4. In a flashlight; a casing; a reflector in said casing; a lamp bulb in said casing in operative relation with said reflector; a diffusing screen movably mounted in said casing in operative relation with said lamp bulb; a switch movably mounted upon said casing; means for mechanically connecting said screen with said switch comprising a yoke rigidly secured to said screen and said switch and movable therewith; said means for electrically connecting said lamp bulb with said switch comprising a conductor in operative relation with said switch and movable with said yoke.

5. In a flashlight; a casing; a lamp bulb in said casing; a diffusing screen movably mounted in 70 said casing in operative relation with said lamp bulb; a switch, including a pair of electrical contacts, mounted upon said casing for movement as a unit; conductive means electrically isolated from said casing and operably connecting said 75

switch and said lamp bulb in all positions of said switch; and means rigidly connecting said switch and said diffusing screen whereby bodily movement of said switch as a unit moves said diffusing screen with respect to said lamp bulb to control the character of the projected light beam.

5. In a flashlight; a casing; a lamp bulb in said casing; a switch movably mounted upon said casing; a diffusing screen in operative relation with said lamp bulb; a support for said diffusing screen rigidly secured to said switch and movable therewith; means for completing the electric circuit between said switch and said lamp bulb comprising a conductor secured to said support and movable therewith; and a suitable dielectric for isolating said conductor from said support.

6. In a flashlight; a casing; a lamp bulb in said casing; a switch movably mounted upon said casing; a diffusing screen movably mounted in said casing in operative relation with said bulb; a support for said screen rigidly secured to said switch; and means for completing the electric circuit between said switch and said lamp bulb comprising a movable conductor rigidly secured 25 to said support, and a stationary resilient conductor in conductive relation with said lamp bulb and in operative resilient engagement with said movable conductor.

7. In a flashlight; a casing; a lamp bulb in said casing; a switch mounted upon said casing and movable with respect thereto and with respect to said lamp bulb into a plurality of adjusted operating positions; said switch being operable to control the luminous condition of said lamp bulb 35 in any of said positions; a support within said casing rigidly secured to said switch; a diffusing screen rigidly secured to said support in movable relation to said lamp bulb; and means for maintaining said switch in said adjusted positions comprising a resilient member secured to said switch in resilient engagement with said casing.

8. In a flashlight; a casing; a lamp bulb in said casing; a switch mounted upon said casing and movable with respect thereto and with respect to said lamp bulb into a plurality of adjusted operating positions; said switch being operable to control the luminous condition of said lamp bulb 40 in any of said positions; a support within said casing rigidly secured to said switch; a diffusing screen rigidly secured to said support in movable relation to said lamp bulb; and means for maintaining said switch in said adjusted positions comprising a resilient member secured to said switch in resilient engagement with said casing.

9. In a flashlight; a casing; a lamp receiving

socket secured in fixed electrically insulated relation to said casing; a resilient conductor connected to said lamp receiving socket; a second conductor attached to said yoke and insulated therefrom; said second conductor adapted to movably engage said first conductor; and a second resilient means attached to said member and adapted to extend through an opening in said casing to engage said second conductor.

10. In a flashlight; a casing; a lamp receiving socket secured in fixed electrically insulated relation to said casing; a reflector secured to said casing and having an opening in alignment with but of larger diameter than said lamp receiving socket; a translucent screen surrounding said lamp receiving socket in alignment with said opening for movement therethrough; a member slidably connected on the outside of said casing; a yoke secured to said screen and straddling said lamp receiving socket; said yoke being connected at its opposite end to said member through openings in said casing; resilient means for maintaining said yoke and member in frictional engagement with said casing; resilient means for maintaining said yoke and member in frictional engagement with said casing; a resilient conductor connected to said lamp receiving socket; a second conductor attached to said yoke and insulated therefrom; said second conductor adapted to movably engage said first conductor; a second resilient means attached to said member and adapted to extend through an opening in said casing to engage said second conductor; and stop means for limiting the movement of said member, yoke and screen.

11. In a flashlight; a casing having an opening in a side wall thereof; a lamp receiving socket connected in fixed electrically insulated relation to said casing; a resilient conductor electrically connected to said socket; a switch member mounted in movable relationship on the outside of said casing and covering said opening; a second member slidably mounted on the inside of said casing opposite said switch member and rigidly connected thereto, said second member having a recessed portion extending through said opening to limit movement of said switch member; a conductor mounted in insulating relationship on said second member and slidably engaging said first mentioned conductor; and resilient means fixed at one end to said switch member and extending through an opening therein and the opening in the side wall of the casing, and adapted to engage said second mentioned conductor in any position to which said switch member may be moved.

HERMAN G. GRAUBNER.
